CAR

Charles E. Windecker, Painesville, Ohio

Application May 12, 1932, Serial No. 610,885

11 Claims. (Cl. 214—83)

This invention relates to portable containers for bulk industrial products, and constitutes a modification of the invention shown in my application Serial No. 607,293 filed April 25, 1932. 5 The term "cars" adopted as a title relates not only to railway cars but also to highway conveyances. The main objects of the invention are the provision of a readily sealed container for the transportation of such substances as cement, 10 coal, grain, fertilizers, paint-pigments, china-clay, bauxite, fuller's earth and other ores, sugar, salt and dry chemicals generally such as borax, soda, blue and green vitriol, etc. whereby the materials being transported may be adequately protected from weather, moisture and circulation 15 of air and having mechanical discharging means located at a higher level than heretofore, thus facilitating disposal of the contents; the provision of means to reduce the cost and increase 20 the speed of loading and emptying a car of bulk material of the general nature described; the provision of a self-loading and unloading car having large capacity per foot of car length; the provision of an improved type of car for the 25 transportation of bulk materials having improved means for breaking up and discharging its contents through a single opening thus enabling the disposition of the same by power-operated conveyors; the provision of a new and 30 improved mode of supporting and rotating a rotatable storing or transporting container; the provision of a new and improved means of securing such a container against movement; while further objects and advantages of the invention 35 will become apparent as the description proceeds.

A preferred form of my invention is illustrated in the drawings accompanying and forming a part of this application wherein Fig. 1 is a side elevation of a railway-car containing my 40 improvements; Fig. 2 is a vertical cross-sectional view corresponding to the line 2—2 of Fig. 1 and looking in the direction indicated by the arrows; Fig. 3 is a view of the discharge end of the car, certain parts of the hopper and closure being 45 broken away; Figs. 4 and 5 are cross-sectional details of a part of the supporting chain shown in Figs. 2 and 3 and showing alternative features of construction. Figs. 6 and 7 are cross-sectional views corresponding to lines 6—6 and 7—7 50 of Fig. 1; and Figs. 8, 9, and 10 are cross-sectional detail views showing a preferred means of providing for longitudinal yielding under shock corresponding to the lines 8—8, 9—9 and 10—10 55 respectively of the several views.

55 Describing by reference the parts shown in

these drawings, but without intent to limit myself thereto, I represents a hollow, cylindrical, metal tank made in a single compartment, without partitions, and mounted with its axis horizontal and longitudinally arranged upon a rectangular frame 2, here shown as a flat platform. In the present embodiment this frame constitutes the body of a railway car carried by the usual trucks having wheels 3—3, although within my invention the tank might equally well be mounted on highway wheels, or might even be stationary since I apprehend in some instances a tank of this type may prove valuable for storage purposes. If and when employed as a railway car, this frame comprises longitudinal sills 4 and transverse bolsters 5, the platform projecting sufficiently at each side of the tank 1 to constitute a runway for the trainmen.

Encircling the tank near each end is a circular tire 8 which runs on or between the various rollers carried by the platform or frame by means of which the tank is rotatably supported. The supporting is effected by means of a plurality of rolls 9 each journaled upon a horizontal pintle 11, these pintles being flexibly connected by 20 means of link-bars into the form of a chain, the terminal pintles 10—10 being located one at each side of the tank and pivoted on horizontal axes to uprights 12—12 which are rigidly carried by the frame. These uprights are preferably continuous with an over-arching yoke 13 which both joins the uprights together to afford 25 added strength and also encircles the tank to ensure greater safety. These uprights are also preferably braced longitudinally as indicated at 30 14. By mounting the supporting rolls in a flexible manner they are enabled to conform at all times to the shape of the tires 8, thereby causing 35 all of the rolls to participate at all times in supporting the weight of the tank and its contents, since a commercial load for such a car may be any weight from twenty tons to fifty, sixty tons or more.

When the tank is mounted upon a portable frame, provision is also preferably made for securing it rigidly to that frame during transit. These provisions preferably relate both to the prevention of bodily separation between the tank and frame and also to the prevention of rotation of the tank. In the present embodiment I have 45 illustrated means cooperating to this end, such means participating to some extent in both functions. In Fig. 3 I have shown the yoke 13 as provided above the tank with clamping members 16 movable by suitable adjusting elements such 50 55

as the screws 15 to secure or release the tank as may be desired.

Further to prevent rotation and to absorb and transmit the longitudinal shock or thrust from the tank to the supporting frame I have shown a second expedient comprising a radially projecting metal block 20 fastened to the tank exterior and rotatable between projecting portions of a slidible block 23, the block 23 being held by multiple springs 27 midway between two fixed blocks 21—21, rigidly secured to the frame or platform. I have shown the block 20 as made hollow to save weight. Interposed at each end of the block 20 between it and the adjacent block 23 is a transverse wedge-member 22 held in place in any simple and suitable manner, such as by means of a nut 24 screwed on a threaded extension 25 of said wedge. Suitable washers or spacers 26 may be employed in cooperation with these nuts as will be understood by those skilled in the art. The block 23 here takes the form of a transversely recessed member, longitudinally slidable along the top of the sill 4 between guides 29, and having abutment portions at its ends which the wedges 22 engage. When these wedges are in place the tank or container is not only prevented from turning, by the action of the guides 29, but is also held yieldingly by the springs which in the case of an impact between different cars absorb the inertia of the loaded container. In the case of two such cars each containing a load of fifty tons the longitudinal strain produced when one of these cars moving comes into endwise contact with the other of these cars at rest, according to the degree of speed and care ordinarily encountered in railroad yard and switching practice, is a very substantial figure.

Carried by the platform 2 at the end of the tank is a stationary hopper 36 here shown as supported on four legs 37 and embracing a spout 34 projecting from the center of the end of the tank so as to permit its rotation but prevent leakage of the material. The hopper is made slightly funnel shaped at its bottom 39 and is so constructed as to permit the attachment within the opening 38 of any suitable means (not shown) of conveying the material away during the unloading operation. Blades 32 fixed interiorly of the tank are so made as to lift the material when the tank is rotated about its longitudinal axis and discharge it through the opening 33 into the hopper. During transit the spout 34 is sealed shut by a removable plate 35 held by any suitable means, the arrangement here shown consisting of nuts and bolts. Access to this closure plate 35 through the hopper may be had by means of a door 31 which is hinged to the exterior of said hopper. The blades 32 extend to the wall of the tank and are so shaped and inclined as to lift and feed the contents through the spout 34 as the tank is revolved in the appropriate direction.

The interior of the tank is provided throughout its length with one or more helical blades 40, spiraled in such direction that upon rotation of the tank in the direction to discharge its contents through the discharge hopper said contents are moved toward the discharge hopper from the opposite end of the tank. At the discharge end of the car these blades 40 terminate at or near the zone defined by the blades 32. In Fig. 1, for purpose of clarity, I have shown only one blade; in Fig. 2, I have shown two helical blades, and in Fig. 6, I have shown three blades.

Any suitable or convenient expedient may be employed to rotate the tank, the preferred ex-

pedient being to furnish the same with a circumferential sprocket 42 operatively engaged by a chain 43 meshing with a cooperating sprocket 44 which is driven by an electric motor 45 (or other suitable power source) carried by the platform 2 (or otherwise) and working through a speed-reduction gear-set 46. An electric motor is, of course, applicable only under conditions where electric power is available at the unloading station, and sometimes also at the loading station, but it is obvious that with only a small change in construction the device can be arranged for operation by steam, gasoline, air or other power.

The procedure of filling the car depends to some extent upon the nature of the materials. Sometimes some materials, like cement when properly aerated, will of their own nature flow sufficiently throughout the tank as to require the opening of only a single aperture 48. But in the case of some materials a plurality of apertures 48 are preferably employed for the introduction of the material. In case a full load is not obtained after such measures the covers may be returned to the loading apertures and the car rotated in one direction or the other, thus spreading the load lengthwise and making possible the addition of a further quantity of material.

I have shown the end opposite the discharge hopper as provided with a manhole having a removable manhole-cover 47 to facilitate cleaning, inspection, and repairing.

In order to unload the tank, the car is so positioned as to allow the introduction into the opening 38 of a screw conveyor, belt conveyor, or any other suitable means of conveyance. The closure 35 and the wedges 22 are then removed and the tank rotated in such direction as will move the material toward the discharge end of the tank. In the case of materials which tend to pack or solidify in transit the first revolution of the tank is the most difficult but generally results in a substantial breaking up of the load, after which the continued rotation not only moves the material to the outlet but also keeps it pulverized and prevents it from caking or blocking the outlets as oftentimes happens with a container which is stationary during evacuation.

It will be understood that while I have described my invention in detail and pointed out those constructions which seem to me most satisfactory for all around use, there are conditions existing in the specific arts which require modifications from the specific constructions and designs here shown, and I do not limit myself in any wise except as recited in my several claims which I desire may be construed each according to its own limitations and independently of limitations contained in other claims.

Having thus described my invention what I claim is:

1. A car for transporting dry granular and pulverized materials comprising in combination, an elongated, weather-tight compartment mounted with its major dimension horizontal and longitudinal, a discharge hopper at the end of said compartment, and conveyor means inside said compartment for moving all the materials in said car to said hopper.

2. A car for transporting dry granular and pulverized materials comprising in combination, an elongated, weather-tight tank mounted with its major dimension horizontal and longitudinal, a single hopper at the end of the tank and conveyor means inside said compartment adapted

when said tank is rotated in one direction to move its solid contents away from said hopper and when moved in the opposite direction to move the such contents towards said hopper.

5 3. A car for transporting dry granular and pulverized materials comprising in combination, a frame, a metal tank located on said frame and having a wall which defines a surface of revolution about an axis which is horizontal and 10 lengthwise of said car, means supporting said tank for rotation about said axis, a stationary hopper at the end of said tank, said hopper having an inlet opening in its side and an outlet opening in its bottom and said tank having an 15 axial discharge opening registering with said inlet opening, means for rotating said tank about its axis, and internal blades fixed inside said tank and inclined relative to the tank axis whereby the tank contents are moved length- 20 wise when said tank is rotated.

20 4. A car for transporting dry granular and pulverized materials comprising in combination, a frame, a stationary hopper carried by said frame and an elongated, horizontal, rotatable 25 tank carried by said frame and extending to said hopper, said tank having a discharge opening delivering into said hopper in all positions of said tank, mechanical conveyor means inside said tank adapted to eject the solid contents of said tank through said opening and a closure for said opening.

30 5. A car for transporting dry granular and pulverized materials comprising in combination, a frame, a metal tank located on said frame and having a side wall which defines a surface of revolution about an axis which is horizontal and lengthwise of said car, said tank having an axial discharge opening in an end wall, means supporting said tank for rotation about said axis, 35 means for rotating said tank about said axis, and helical blades affixed to the tank interior, said tank having pick-up discharge blades at the ends of said helical blades, and said pick-up discharge blades being so fixed to the interior 40 of said tank as to discharge through said discharge opening.

45 6. A car for transporting dry granular and pulverized materials comprising in combination, a frame, a cylindrical metal tank located on said frame with its axis horizontal and lengthwise, said tank defining a single compartment and having a discharge provision located in the center of the end of said tank, and means inside 50 said tank for moving all of the material therein to the discharge end of said tank, raising and discharging said material through said discharge provision during the unloading operation.

55 7. A car for transporting dry granular and pulverized materials comprising in combination, a frame, a metal tank located on said frame and having a wall which defines a surface of revolution

5 about a horizontal lengthwise axis, means for rotating said tank about its axis, and means for supporting said tank characterized by a plurality of rollers angularly and longitudinally spaced about the bottom half of said tank, means for yieldingly supporting said rollers whereby all the same bear against said tank at all times, and means for permitting a limited degree of axial movement of said tank relative to said rollers.

10 8. A car for transporting dry granular and pulverized materials comprising in combination, a frame, a metal tank located on said frame and having a wall which defines a surface of revolution about a horizontal lengthwise axis, means for rotating said tank about its axis, and means 15 for supporting said tank characterized by a plurality of sets of rollers carried by said frame and spaced lengthwise of said tank, a longitudinally slidable member carried by said frame, spring means yieldingly opposing longitudinal 20 movement of said member, and means for rigidly securing said tank to said member.

25 9. A car for transporting dry granular and pulverized materials comprising in combination, a frame, a metal tank located on said frame and having a wall which defines a surface of revolution about a horizontal lengthwise axis, inclined blades fixedly secured inside said tank, means supporting said tank for rotation about said axis, a power source carried by said frame, operative 30 connections from said power source to said tank for rotating said tank continuously during the discharging operation, said tank having an axial discharge aperture at its end and a hopper constantly in receiving relation to said aperture 35 during such rotation of the tank.

40 10. A car for transporting dry granular and pulverized materials comprising in combination, a frame, a hollow metal tank located on said frame and having a wall which defines a surface of revolution about a horizontal lengthwise axis, means for supporting said tank for rotation about said axis, means for rotating said tank about its axis, and means for securing said tank yieldingly to said frame, said means comprising interspaced 45 blocks carried by said tank and frame, wedge members adapted to be interposed between certain of said blocks, and longitudinal springs adapted to be interposed between other of said blocks to absorb the inertia of the loaded tank 50 upon impact between cars.

55 11. A car for transporting dry, granular, and pulverized material comprising the combination of a cylindrical tank, a discharge opening in the central portion of the end of said tank, means for conveying all of the material from the interior of said tank through said discharge opening upon rotation of said tank, and an enclosed hopper surrounding said discharge opening.
